UNITED STATES PATENT OFFICE.

EDWARD T. BURROWES, OF PORTLAND, MAINE.

DESIGN FOR A CURTAIN.

SPECIFICATION forming part of Design No. 29,953, dated January 3, 1899.

Application filed November 19, 1898. Serial No. 696,947. Term of patent 14 years.

To all whom it may concern:

Be it known that I, EDWARD T. BURROWES, a citizen of the United States, residing at Portland, in the county of Cumberland and State of Maine, have invented and produced 5 a new and original Design for Curtains; and I do hereby declare the following to be a full, clear, and exact description of the same, reference being had to the accompanying drawing, forming a part thereof.

This invention relates to a new and original design for curtains; and it consists generally in the configuration and relative arrangement of parts hereinafter described, defined in the claim, and shown in the accompanying drawing.

The design is illustrated in elevation in the single figure shown in the drawing, it being understood that the reverse side is in all material and substantial respects the same as 20 that shown.

In the drawing, A designates a window curtain or shade having on its lower edge the bottom portion or "leather" B. This bottom portion has at or near its center portion 25 and slightly above the plane of the center the transverse pocket C, at the opposite ends

of which, projecting beyond the edges of the part B, are the projections c. At or near the lower edge of the part B is a pocket D, which 30 extends entirely across the part B and is of substantially uniform diameter throughout. At the opposite ends of this pocket D are the ornamental knobs E, which project slightly beyond the ends of the pocket. These knobs 35 are suitably finished, so as to afford an attractive contrasting feature for the lower edge of the curtain.

The ornamental feature of the design is the curtain having the part B with the associated pockets, the upper pocket having the projections at its ends and the lower pocket having the fanciful knobs at its ends.

Having thus described the invention, what I claim as new, and desire to secure by Letters 45 Patent, is—

The design for a curtain, substantially as shown and described.

In testimony whereof I affix my signature in presence of two witnesses.

EDWARD T. BURROWES.
